CHECKER-CLEANING APPARATUS

Charles J. Burch, Lower Makefield Township, Bucks County, Pa., assignor to United States Steel Corporation, a corporation of New Jersey

Filed Mar. 19, 1963, Ser. No. 266,294

12 Claims. (Cl. 15—317)

This invention relates to an improved apparatus for cleaning furnace checkers.

Some types of furnaces, such as open hearths used in steelmaking, are equipped with checker chambers for pre-heating the combustion air. The chambers contain checker bricks which are heated by directing products of combustion from the furnace over them. Periodically the furnace is reversed, one set of checkers being used to pre-heat air while another is heating. As the furnace operates, soot and other foreign material accumulate in the checkers and must be cleaned out at intervals. Conventional practice is to insert lances manually through ports in the chamber wall and inject high pressure steam or water through the checkers to clean them, although mechanical devices for handling lances also are known and have had limited use. Handling the lances manually is a difficult and unpleasant task, yet machines used previously have not been entirely satisfactory. They propel a lance in and out a port with straight-line movement, but do not allow an operator otherwise to guide the lance. Sometimes an operator needs to tilt a lance or swing it sideways within a port to clear an obstruction, yet previous machines lack any provision for such movement.

An object of the present invention is to provide an improved lance-handling machine which effectively supports a lance and propels it into and out ports in a chamber wall, yet allows an operator both to control movement of the lance and to guide it as needed.

A further object is to provide an improved machine of the foregoing type which has flexibly supported power-driven pinch rollers for propelling the lance and allowing it to tilt or swing sideways within a port.

A further object is to provide an improved checker-cleaning apparatus in which the lance itself carries control means for the lance-handling machine and handles for guiding the lance within a checker chamber.

In accomplishing these and other objects of the invention, I have provided improved details of structure, a preferred form of which is shown in the accompanying drawings, in which:

FIGURE 1 is a partly diagrammatic end elevational view of a lance-handling machine constructed in accordance with my invention and positioned adjacent a conventional checker chamber;

FIGURE 2 is a top plan view of the machine on a larger scale;

FIGURE 3 is a side elevational view of the machine;

FIGURE 4 is a vertical section on line IV—IV of FIGURE 3;

FIGURE 5 is a side elevational view of a lance of my preferred construction; and

FIGURE 6 is a vertical section on line VI—VI of FIGURE 5.

FIGURE 1 shows diagrammatically a portion of a conventional checker chamber which includes a wall 10 and checker bricks arranged in vertically spaced courses 12, 12a and 12b. The wall has vertically spaced series of ports 13, 13a and 13b located respectively above the uppermost course and in alignment with spaces 14 and 14a between the other courses. A portable machine 15, constructed in accordance with my invention, is positioned adjacent wall 10 to insert a lance 16 through the different ports. When the lance is inserted in the uppermost or middle ports 13 or 13a, I mount a removable platform 17

2

behind the machine to accommodate the operators (preferably two). When the lance is inserted in the lowermost ports 13b, I remove the platform. The platform rests on portable stands 18. Preferably the platform carries a removable support 19 for steadyng the overhanging portion of the lance, since the lance may have a length of forty feet or more.

As best shown in FIGURES 2, 3 and 4, my lance-handling machine 15 includes a rigid chassis formed of a base 21, four angle iron columns 22 22a, 22b and 22c extending upwardly from the base, and cross members 23, 23a, 23b and 23c interconnecting the columns above the base. The four columns define a vertical frame which is square when viewed from above (FIGURE 2). The chassis is supported on wheels 24. Preferably the machine is self-propelled, and the base carries a conventional battery-operated drive motor 25 and battery 26 for this purpose. The side of the frame away from the furnace carries outriggers 27 and 27a fixed to the lower portions of columns 22c and 22b respectively and reinforced with gussets 28 and 28a. The outer edges of the outriggers carry vertical sleeves 29 which receive retractable legs 30. When a lance is inserted in the uppermost ports 13, I lower these legs into engagement with the floor beneath the machine to assure stability and prevent overbalancing. Otherwise I raise the legs to an inoperative position clear of the floor. I retain the legs in their different positions with pins 31 removably inserted in transverse openings in the sleeves and legs.

Base 21 carries a pedestal 33 outside columns 22 and 22c. The pedestal carries a winch 34 and a drive motor 35 connected to the winch through a speed-reducer 36. The outer face of columns 22b and 22c carry aligned bearings 37 in which a shaft 38 is journaled. The shaft carries a drum 39 of relatively large diameter and drums 40 and 40a of smaller diameter. A cable 41 is wound around winch 34 and drum 39 for driving the shaft from the winch. Pulleys 42 and 42a are journaled to cross members 23 and 23a respectively adjacent the upper ends of the columns. Vertically movable left and right roller housings 43 and 43a are loosely confined within the frame formed by the columns. A cable 44 is wound around drum 40, reeved over pulley 42 and attached to a bracket 45 which extends from the outer end of the left roller housing 43. Another cable 44a bears a similar relation to drum 40a, pulley 42a and housing 43a, whereby rotation of shaft 38 raises or lowers both housings. Since the cables are flexible, they allow the housings to tilt and also move horizontally within the confines of the frame. The sides of the housing carry semicircular bumper plates 46 which are engageable with the inside faces of the columns. Preferably the ends of the housings carry safety hooks 47 flexibly attached thereto and engageable with slots 48 in the columns to prevent accidental dropping, yet not interfere with the limited tilting and horizontal movement.

As best shown in FIGURE 2, coupler rods 50 are fixed to the sides of the left housing 43, and sleeves 51 are fixed to the sides of the right housing 43a. The sleeves slidably receive the rods to hold the two housings in alignment. A double-acting fluid pressure cylinder 52 (preferably pneumatic) is fixed within the left housing 43 and contains a reciprocable piston and piston rod 53. The end of the rod is connected to a clevis 54 fixed within the right housing. Preferably the piston rod is formed of two parts connected by a sleeve 55, whereby its effective length can be varied. Reversible drive motors 58 and 58a and speed reducers 59 and 59a operatively connected therewith are mounted within housings 43 and 43a respectively. Pinch rollers 60 and 60a are fixed to stub shafts 61 and 61a which extend upwardly from the speed reducers 59 and 59a. It may be noted that the housings form a support for the pinch rollers.

Lance 16 is held between rollers 60 and 60a. Cylinder 52 has the usual connections which lead to a suitable control valve (not shown) and thence to a source of fluid pressure, preferably compressed air. When I wish to insert or remove a lance, I operate the cylinder in a direction to project the piston rod 53 and thus separate the housings 43 and 43a and rollers 60 and 60a. When I wish to grip the lance, I operate the cylinder in the opposite direction to bring the housings and rollers together. I operate motors 58 and 58a to turn the rollers to propel the lance. I adjust the pressure so that the rollers normally move the lance, but to allow slippage in the event the lance encounters an obstruction.

As FIGURES 1 and 5 show, lance 16 is formed of an elongated tube which carries a conventional nozzle 62 at the end inserted in the checker chamber. When bricks of the uppermost course 12 are cleaned, it is preferable to use a lance which has a broad flat nozzle. When bricks of the other course are cleaned, it is preferable to use a lance which has a more narrow rounded nozzle to facilitate getting it past obstructions. In either event the nozzle has a downwardly directed outlet. An inlet hose 63 is connected to the outer end of the lance to supply steam or water. The outer end of the lance also carries handles 64. Since the lances wear rapidly and are expendable, the handles preferably are removable to enable them to be installed on new lances. As best shown in FIGURES 5 and 6, an annular collar 65 and a pair of opposed keys 66 are welded to the lance. The handles are fixed to an annular hub 67 which fits around the lance and has keyways to receive the keys 66. The hub abuts the collar 65 and on its upper edge carries a pivoted latch 68 which fits over the collar to hold the handles in place.

A pair of radially extending braces 69 are fixed to the upper portion of hub 67. These braces support a rectangular receptacle 70 which is open at its top. The receptacle is adapted to receive a switch box 71 which has push buttons for controlling operation of motors 58 and 58a. As best shown in FIGURES 3 and 4, a bracket 72 projects from columns 22 and 22c and carries motor starters 73 and 74, a junction box 75 and a switch box 76, which has push buttons for controlling the winch motor 35. Another junction box 77 is mounted on columns 22b near its lower end (FIGURE 3). A relatively long electric cord 78 connects the junction box 77 and switch box 71. Column 22b carries cleats 79 around which I wind cord 78 when the machine is not in use. A series of rigid conduits 80 carry electrical wiring between the junction box 77 and the motor starter 73, between the latter and the proximity of the roller housings 43 and 43a, between the switch box 76 and the motor starter 74, between the latter and the winch motor 35, and between the junction box 75 and the two motor starters. An electric cord 81 through which the machine is energized is connected to the junction box 75. Bracket 72 also carries a cleat 82 around which I wind cord 81 when the machine is not in use. Other electric cords 83 extend from conduits 80 to the roller housings 43 and 43a. Since the electric circuits follow well-known principles, I have not shown nor described them in detail.

In operation, the machine 15 is positioned adjacent wall 10 as shown in FIGURE 1, and platform 17 is mounted behind the machine and a support 19 mounted on the platform. Winch 34 is operated to raise the roller housings 43 and 43a to the top of the frame formed by columns 22, 22a, 22b and 22c, and the safety hooks 47 inserted in the uppermost notches 48. Legs 30 are lowered into engagement with the floor. A lance 16 is inserted and gripped between rollers 60 and 60a by the steps already described, and the switch box 71 is inserted in the receptacle 70 of the lance. Two operators standing on platform 17 grasp the respective handles 64, and one of them actuates a switch in the switch box 71 to start motors 58 and 58a. These motors drive the rollers 60 and

60a in a direction to propel the lance into the checker chamber through the uppermost port 13. The stream of water or steam is turned on to blow soot from the uppermost course 12 of checker bricks. The operators 5 guide the lance as it moves into the chamber, and in the event it encounters an obstruction, they steer it past. The loose mounting of the roller housings 43 and 43a affords the necessary flexibility. If the obstruction is too large, the rollers can slip against the lance. After the lance is fully inserted, one operator actuates a switch in box 71 to reverse the direction of motors 58 and 58a and withdraw the lance, which thus makes a second pass over the bricks. After cleaning the uppermost course in this manner, the operators lower the roller housings successively to their other positions and repeat the procedure to clean the other courses 12a and 12b. In each instance they use a lance which has an appropriate nozzle 62. They use a shorter support 19 in cleaning the middle course, and remove the platform and support in cleaning the lowermost course.

From the foregoing description it is seen that my invention affords a simple apparatus for cleaning checker-work, yet allows flexibility which prior apparatus lacks. The lance is under full control of the operators at all times as it moves into and out of a checker chamber. Thus the lance readily moves past obstructions and does not loosen bricks or otherwise damage the checker chamber.

While I have shown and described only a single embodiment of my invention, it is apparent that modifications may arise. Therefore, I do not wish to be limited to the disclosure set forth but only by the scope of the appended claims.

I claim:

1. A lance-handling machine comprising a base, a vertical frame fixed to said base, a movable support loosely confined within said frame, means on said base operatively connected with said support for raising and lowering it but allowing it to tilt and to move horizontally within the confines of said frame, pinch rollers carried by said support for rotation on vertical axes and being positioned at the same level, means carried by said support for separating said rollers horizontally to permit insertion of a lance therebetween and drawing said rollers together to grip the lance, and drive means for said rollers to propel a lance gripped therebetween.

2. A lance-handling machine comprising a base, a vertical frame fixed to said base, a pair of housings loosely confined within said frame, flexible means supporting said housings from the top of said frame and positioning the housings side by side but allowing them to move freely within the confines of said frame, means on said base operatively connected with said flexible means for raising and lowering said housings, respective pinch rollers carried by said housings for rotation on vertical axes and being positioned at the same level, means connecting said housings for separating said rollers horizontally to permit insertion of a lance therebetween and drawing said rollers together to grip the lance, and drive means mounted in said housings and operatively connected with said rollers for propelling a lance gripped therebetween.

3. A lance-handling machine comprising a base, a vertical frame fixed to said base, a pair of housings loosely confined within said frame, flexible means suspending said housings from the top of said frame and positioning the housings side by side but allowing them to tilt and to move horizontally within the confines of said frame, a winch on said base, means operatively connecting said winch and said flexible means for raising and lowering said housings, respective pinch rollers carried by said housings for rotation on vertical axes and being positioned at the same level, slidable coupling means connecting said housings, fluid pressure means operatively connected with said housings for separating the housings and rollers horizontally to permit insertion of a lance between the rollers and drawing the housings and rollers together to grip the lance.

lance, and drive means mounted in said housings and operatively connected with said rollers for propelling a lance gripped therebetween.

4. A lance-handling machine comprising a portable base, columns fixed to said base and defining a vertical frame, a pair of housings loosely confined within said frame, flexible means individually suspending said housings from the top of said frame and positioning the housings side by side but allowing them to tilt and move horizontally within the confines of said frame, a winch and drive means therefor mounted on said base, means operatively connecting said winch and said flexible means for raising and lowering said housings, respective pinch rollers carried by said housings for rotation on vertical axes and being positioned at the same level, coupling rods fixed to opposite sides of one housing, sleeves fixed to opposite sides of the other housing slidably receiving said rods, a double-acting fluid pressure cylinder carried by one housing, a reciprocable piston and piston rod in said cylinder connected to the other housing and operable to separate the housings and rollers horizontally to permit insertion of a lance between the rollers and to draw the housings and rollers together to grip the lance, and drive means mounted in said housings and operatively connected with said rollers for propelling a lance gripped therebetween.

5. A machine as defined in claim 4 comprising also a portable self-propelled chassis on which said base is mounted.

6. A machine as defined in claim 4 comprising also outriggers fixed to said base and frame at one side thereof and retractable legs carried by said outriggers for preventing overbalancing.

7. A machine as defined in claim 4 comprising also a bracket fixed to the outside of said frame, motor starters for both said drive means carried by said bracket, rigid conduits carried by said frame for the electrical wiring, an elongated cord extending from one of said conduits, and a switch for controlling said second-named drive means attached to said cord and adapted to be mounted on said lance.

8. A machine as defined in claim 4 in which the means operatively connecting said winch and said flexible means includes a horizontal shaft journaled to the outside of said frame, pulleys journaled to the top of said frame, drums carried by said shaft, and a cable wound on said winch and on one of said drums, said flexible means being wound on the other drums and reeved over said pulleys.

9. A machine as defined in claim 4 comprising also bumpers carried by said housings and engageable with said columns, and hook flexibly connected with said

housings and engageable with said columns to prevent accidental dropping of said housings.

10. An apparatus for cleaning furnace checkers including an elongated tubular lance and a machine for handling said lance, said machine comprising a base, a vertical frame fixed to said base, a movable support loosely confined within said frame, means on said base operatively connected with said support for raising and lowering it but allowing it to tilt and move horizontally within the confines of said frame, pinch rollers carried by said support for rotation on vertical axes and being positioned at the same level and gripping said lance, means carried by said support for separating said rollers horizontally to permit removal of said lance, drive means for said rollers to 15 propel said lance, and means carried by said lance for controlling said drive means.

11. An apparatus for cleaning furnace checkers including an elongated tubular lance and a machine for handling said lance, said machine comprising a base, a vertical frame fixed to said base, a pair of housings loosely confined within said frame, flexible means suspending said housings from the top of said frame and positioning the housings side by side but allowing them to tilt and to move horizontally within the confines of said frame, a 20 winch on said base, means operatively connecting said winch and said flexible means for raising and lowering said housings, respective pinch rollers carried by said housings for rotation on vertical axes and being positioned at the same level and gripping said lance, means connecting said housings for separating said rollers horizontally to permit removal of said lance, drive means mounted in said housings and operatively connected with said rollers for propelling said lance, and switch means mounted on said lance and operatively connected with said drive means 25 for controlling lance movement.

12. An apparatus as defined in claim 11 including handles removably mounted on said lance, and a receptacle carried by said handles for removably supporting said switch means.
